UNITED STATES PATENT OFFICE.

FERDINAND M. WEGNER, OF BROOKLYN, NEW YORK.

MACHINE FOR UNHAIRING FUR-SKINS.

1,242,400.

Specification of Letters Patent.

Patented Oct. 9, 1917.

Application filed February 14, 1917. Serial No. 148,657.

To all whom it may concern:

Be it known that I, FERDINAND M. WEGNER, a citizen of the United States, residing at Brooklyn, in the county of Kings and 5 State of New York, have invented a new and useful Machine for Unhairing Fur-Skins, of which the following is a specification.

My invention relates to improvements in a machine for unhauling fur skins and it 10 consists in the novel features hereinafter more fully described.

The objects of my improvement are:

First, to produce a machine for unhauling fur skins, having a more perfect action and 15 embodying the sundry features of excellence hereinafter described.

Second, to have said machine, with said improvements embodied therein, as simple and inexpensive as possible.

20 I attain these objects by the mechanism illustrated in the drawings or by any mechanical equivalent or obvious modification of the same.

In the drawings Figure 1 is a vertical section of my machine as viewed from the left side thereof, the section being in a plane flush with the conveyer for the fur skins, and leaving out sundry unessential details, such as fastenings; Fig. 2 is a view of the 25 mechanism, which actuates the cams 54 hereinafter more fully described, also showing the transmission gearing for the brushes. Fig. 3 is a vertical section and Fig. 4 a front elevation, on a larger scale, of the 30 bridge 32, the parallel bars 38 and the shield plates 89, hereinafter more fully described.

Similar numerals and letters refer to similar parts throughout the views of the drawings.

40 11 designates the frame of the machine, to which is secured the stationary vertical bridge 32, over which the fur skin is made to pass by means of the conveyer 33, which is in contact with the rollers 34, 35, 36 and 45 37, carried by the shafts or spindles 15, 16^a, 14 and 16 respectively.

Said bridge 32 is made vertical for the purpose of rendering the operation of clipping the coarse hair of the fur skins visible 50 to the operator, who is thereby enabled to have more perfect and ready supervision of the said operation.

In front of said bridge 32 the rotary brush 29 is supported at each end thereof by a 55 bracket 31, which is secured to said frame 11.

Said brush 29 is rotating on its axis in a counter clockwise direction, as viewed in Fig. 1, and it receives its motion from a gear wheel 75 secured to the roller of said brush 29; said gear wheel 75 is indicated 60 by its pitch line, and it is shown in Fig. 2 as meshing with the gear wheel 74, supported in position by the stud or pin 30, which carries also the sprocket 72, which is operatively connected to the sprocket 71 65 by means of the chain 73.

All gear wheels and sprockets are indicated by their pitch lines in the drawings, and the chains by dotted lines.

Said sprocket 71 is shown in Fig. 2 as 70 secured to the power shaft 12, which is shown in Fig. 1 as supported in position by the bearings 12^a, and which carries also the belt pulley 66^a and the sprockets 66 and 69.

Said belt pulley 66^a is adapted to receive the motion from a suitable motor or flywheel by means of a belt, which is not shown in the drawings.

The pitch line of said sprocket 69 coincides with the hub of the bearing 12^a in Fig. 1.

Said sprocket 66 is connected by means of the chain 67 to the sprocket 65, which is secured to the main driving shaft 13, 85 which is journaled in said frame 11, and which carries also the cam 21, shown in Fig. 1, and the disk 82, which is hereinafter described.

Said cam 21 actuates the lever 22, which 90 is pivotally connected to said frame 11 by means of the pin 17, and which carries the cam roller 23 in contact with said cam 21.

Said lever 22 is shown in Fig. 1 as supporting at its outer end the revolving and 95 rocking spindle 18, which carries the sprockets 68 and 76.

Said sprocket 68 is operatively connected to said sprocket 69 by means of the chain 70, and it revolves said spindle 18 in a clockwise direction, as shown by the arrows.

Said sprocket 76 is operatively connected to the sprocket 77 by means of the chain 78.

Said sprocket 77 is carried by a stud or pin 87, and it rotates the gear wheel 79, 105 which is supported by the same pin 87, which may be secured to said sprocket 77 in any suitable manner. Said gear wheel 79 is shown in Fig. 2 as transmitting its motion to the gear wheel 81 by means of the inter- 110

mediate gear wheel 80, which is in mesh with both gear wheels 79 and 81, and is carried by the stud or pin 88.

Said gear wheel 81 is secured to the roller 5 of the rear brush 28, which revolves therewith in a clockwise direction as shown in Fig. 2.

Said rear brush 28 is pivotally supported at each end thereof by the extension 25 of 10 each of a pair of arms 24, pivotally connected at the lower end thereof to said spindle 18.

Said extensions 25 have each a slot 26 for adjustably connecting the same to said 15 arms 24 by means of the set-screws 27, 27.

Said studs or pins 87 and 88 may be supported by suitable bearings connected to said extensions 25 of said arms 24.

Said arms 24 are imparting a reciprocating motion to the revolving and rocking rear brush 28, the motion of which is also compounded with that of the pair of links 63, one of which is shown in Fig. 1 as pivotally connected at one end thereof to 25 the bracket 64, which is rigidly secured to the frame 11, by means of the pin 63^a, and at the other end to one of the extensions 25 of said arms 24, by means of the pin 63^b.

The said links 63 cause said rear brush 28 30 to be brought at a certain point of its cycle of motion, toward the upper edge of said bridge 32, as is hereinafter more fully described.

The brushes 29 and 28 are shown in Fig. 35 2 without bristle, for the sake of clearness.

The front brush 29 brushes the fur of the skin in the direction of its natural inclination, which is downwardly on the front side of the bridge 32; the rear brush 28 is 40 brushing the fur of the skin against its natural inclination, and the reciprocating motion is imparted to it for the purpose of permitting the periodical action of the knives 41 and 42, hereinafter more fully described.

The action of the rear brush 28 is supplemented by the horizontal combing bar 39, which is carried by a pair of oscillating arms 40 at the upper ends thereof.

Said arms 40 are pivotally connected at their lower ends to said arms 24, and their motion is modified by a pair of links 60, which are pivotally connected, each at one end thereof, to the frame 11, by means of the 50 pin 61, and, at the other end, to one of said arms 40 by means of the pin 62.

The object of both the rear brush 28 and the combing bar 39 is to keep the soft fur from being clipped while the stiff hairs of 60 the skin, resisting the action of both the rear brush and the combing bar, is protruding upward, and is clipped off.

The clipping is accomplished by the horizontal blade or knife 41 and the horizontally moving inclined blade 42, which are

carried by the horizontal slide bars 48 and 46 respectively; said slide bars 48 and 46 terminate at each end in the sockets 49 and 45 respectively, which sockets are adapted to slide on a pair of guide bars 51, which are 70 supported at their ends by the bosses 52.

Said slide bars 48 and 46 have each on the underside, near each end thereof, the pair of lugs 50 and 47 respectively, which lugs 50 and 47 are pivotally connected to the oscillating arms 53 and 53^a respectively by means of the pins 58 and 59 respectively. 75

Said blade 41 is secured directly to the underside of the slide bar 48 thereby leaving a maximum of room for said front brush 80 29, and the motion imparted to it by the arm 53 is so timed that said blade 41 is pausing during the operation of the clipping of the hair.

This is accomplished by means of the slot 85 55 in each of a pair of oscillating members 54, which slot 55, is engaging the pin 55^a on each of said arms 53, thereby oscillating the same; said slot 55 is shown in Fig. 1 as consisting of an arc of a circle at its upper 90 part and concentric with said spindle 16 for about one-fifth of its length, and spiral shaped or cam shaped for the rest of its length at the middle and lower parts thereof; the circular part of the slot 55 passes the pin 55^a without moving it in either direction, thereby causing the arm 53 and blade 41 to pause or rest; the spiral shaped part of said slot 55 moves said pin 55^a, thereby also moving said arm 53 and blade 41. 100

Each of said oscillating members 54 is secured to said spindle 16, and an oscillating motion is imparted to said spindle 16 by means of the arm 85 and connecting rod 84, shown in Fig. 2 as pivotally connected at 105 its upper end to said arm 85 by means of the pin 86, and at its lower end to the disk 82 by means of the pin 83; said disk 82 is secured to the main driving shaft 13, as hereinbefore described. 110

The conveyer roller 37, above described, is revolving on said spindle 16.

Said oscillating members 54 have each an integral extension or short arm 56, for transmitting the oscillation to each of said arms 115 53^a by means of links 57, which are pivotally connected to said arms 56 and said arms 53^a by means of the pins 57^b and 57^a respectively.

Said arms 53^a are imparting to the slide 120 bar 46 a motion, which has a greater amplitude than that imparted to the slide bar 48 by the arm 53, and the blade 42, carried by said slide bar 46, does not pause during the operation of clipping.

Said blade 42 is not directly secured to said slide bar 46, but to the cross-bar 43, which has horizontal elements parallel to the slide bar 46, but the cross-section of which is shown in Fig. 1 as inclined at an 130

angle of about fifteen degrees from a vertical position; but I do not restrict myself to this particular angle.

The cross bar 43 is pivotally connected 5 near its ends and at the rear thereof by means of the ears 43^a to the lugs 44 of the slide bar 46 near the ends thereof.

This construction having said blade 42 nearly vertical allows the blade 42 to be set 10 cured in position more neatly than when both blades are horizontal; and the pivotal connection of said ears 43^a to said lugs 44 permits the more easy disengagement of said blade 42 from said blade 41 during the 15 separating phase of the motion of said blades 41 and 42.

To protect the soft fur on the sides of the skin I employ certain brass shield plates, and I provide the pair of parallel bars 38 to 20 receive the said shield plates 89, shown in Figs. 3 and 4, therebetween, and to which said shield plates may be fastened by set screws 90 adapted to fit through openings in one of said bars 38, as shown in Figs. 3 25 and 4.

The shield plates themselves may be of any standard or special shape.

The operation of my machine for unhauling fur skins is as follows:

30 A fur skin is fastened on to the conveyer 33 above and to the left of the roller 36, with its hair naturally inclined toward the right; the conveyer is slowly fed forward, in the direction shown by the arrows, by a 35 feed mechanism of any standard construction, not shown in the drawings; the fur skin is passed under the roller 37 and up the bridge 32.

While passing over the sharp crest of said 40 bridge, the rear brush 28 is brought over said bridge 32, and it brushes the hair in a direction contrary to that of its natural inclination, the stiff hair resist this action of said brush 28, and they protrude 45 upwardly in a nearly vertical direction above the crest of said bridge; the rear brush 28 is then lowered by the mechanism, which actuates it, and the combing bar 39 is then brought into action to keep down 50 the soft hair released by said brush 28; the knives 41 and 42 are then brought into action, shearing off the coarse hair therebetween; the knives then separate while the fur-skin is fed forward a short distance, 55 the combing bar 39 is brought out of the way of the rear brush 28, which rises again to the crest of the bridge, and the operation of cutting the coarse hair is repeated for the adjacent short space on the fur skin; 60 the front brush 29 is acting continually in the same position.

The rear brush 28 is acting intermittently.

The two knives 41 and 42 are moving both horizontally, the motion of the rear 65 knife 42 having a greater amplitude, to

allow said rear brush 28 to reach above the bridge 32 before each cutting stroke of the knives.

Many changes could be made in the design of the details of my fur unhauling machine 70 within the scope of my invention.

I do not, therefore, restrict myself to the design of the details of my machine as shown by the drawings, but I intend to include also all mechanical equivalents and 75 obvious modifications of the same.

What I claim as my invention, and desire to secure by Letters Patent, is:—

1. In a machine for unhauling fur skins the combination of a conveyer for the skins, 80 a bridge, a horizontally moving front knife, a horizontally moving rear knife and a means for actuating said knives, said means being adapted to move said knives in opposite directions and said means including a 85 member adapted to act intermittently, thereby allowing said front knife to have a period of rest during the operation of clipping the hair of the skins.

2. In a machine for unhauling fur skins 90 the combination of a conveyer for the skins, a stationary vertical bridge for said conveyer to pass over, a revolving front brush, a revolving and rocking rear brush, a horizontally moving front knife, a horizontally 95 moving rear knife and means for actuating said knives, said means being adapted to move said knives in opposite directions, said means including a member adapted to act intermittently, thereby allowing said 100 front knife a period of rest during the operation of clipping the hair from the skins and said means being adapted to give to said rear knife an amplitude of motion sufficient to permit said rear brush to rise 105 to the crest of said bridge during each stroke thereof.

3. In a machine for unhauling fur skins the combination of a conveyer for the skins, a bridge for said conveyer to pass over, a 110 front knife, a rear knife and a means for actuating said knives, said means being adapted to move said knives in opposite directions, said front knife being secured to a suitable carrier, and said rear knife 115 being secured to a cross bar which is pivotally connected to another carrier, by means of ears, near the ends and at the rear of said cross bar, and suitable lugs on said other carrier, said rear knife thereby being 120 adapted to be readily disengaged from said front knife during the phase of the separating motion of said knives.

4. In a machine for unhauling fur skins 125 the combination of a conveyer for the skins, a bridge for said conveyer to pass over, a front knife, a rear knife and a means for actuating said knives, said means being adapted to move said knives in opposite directions, said front knife being secured 130

to a suitable carrier, and said rear knife being pivotally connected to another carrier and in a position at an angle to said front knife, thereby facilitating the securing of 5 said rear knife in the proper position relatively to said front knife.

5. In a machine for unhauling fur skins the combination of a conveyer for the skins, a bridge, a front knife, a rear knife, and a 10 means for actuating said knives, said means being adapted to move said knives in opposite directions, and said means including an oscillating arm for moving said front knife, a pin on said arm, and an oscillating member 15 having a slot in engagement with said pin, thereby impelling said arm, said slot during part of its outline consisting of an arc of a circle concentric with the pin of said oscillating member, and of a curved part eccentric to said pin during the rest of its out- 20

line, said concentric circular part of said slot allowing said pin and arm to remain stationary during part of the motion of said oscillating member, thereby allowing said front knife to have a period of rest during 25 the operation of clipping the hair of the fur skins.

6. In a machine for unhauling fur skins the combination of a conveyer for said skins, a bridge for said conveyer to pass over, a 30 pair of oppositely moving knives for clipping the coarse hair of said skins, a shield plate for protecting the fur on the edges of the skin and a means for adjustably holding said plate in position, said means comprising two parallel bars horizontally placed, side by side to each other, leaving a space for said plate therebetween, and a means for keeping said plate in position. 35

FERDINAND M. WEGNER.

Copies of this patent may be obtained for five cents each, by addressing the "Commissioner of Patents, Washington, D. C."
